UNITED STATES PATENT OFFICE.

QUINCY D. SCOTT, OF COLUMBUS, OHIO.

ARCH-SUPPORT.

1,372,094.

Specification of Letters Patent.

Patented Mar. 22, 1921.

Application filed November 11, 1920. Serial No. 423,376.

To all whom it may concern:

Be it known that I, QUINCY D. SCOTT, a citizen of the United States of America, residing at Columbus, in the county of Franklin and State of Ohio, have invented certain new and useful Improvements in Arch-Supports, of which the following is a specification.

My present invention relates generally to arch supports useful especially to those who stand on their feet for long periods, and is more particularly an arch support applicable to the outside of a shoe, enabling it to be readily placed in position and removed to suit the convenience of the user.

A further object is the provision of a device of this nature which constitutes a spring support and which may be readily, quickly and effectively adjusted both as to fit and supporting tension.

To the end that these objects and certain other objects may be carried out, my invention resides in a structure such as I will now describe with reference to the accompanying drawing, forming a part of this specification, and wherein,

Figure 1 is a side view showing the practical application of the invention,

Fig. 2 is a rear elevation thereof,

Fig. 3 is a plan view of my improved arch support removed,

Fig. 4 is a vertical section taken substantially on line 4-4 of Fig. 3, and

Fig. 5 is a detail perspective view of my invention.

Referring now to these figures my invention proposes an arrangement applicable to the outside of a shoe such as seen at 10 in Figs. 1 and 2 and for this purpose includes a bridge plate 11 adapted to extend transversely across and beneath the arch of the shoe. I have shown this bridge plate 11 as being substantially flat, but it may if desired be curved to fit the ordinary or special curvature of the arch portion of a shoe.

I also contemplate that this bridge instead of being a plate may be formed of material having sufficient flexibility to enable the same to yield to the form of the shoe arch and snugly seat thereagainst.

The sides of the bridge member 11 are carried in any suitable manner by the lower angular ends 12 of the side portions or extensions 13 of a supporting and tension member 14 of the inverted U-shape shown, whose upper cross bar may incline rear-

wardly as particularly seen in Figs. 1 and 5 so as to adapt it to ready passage and extension across the rear or heel portion of the shoe 10, or across the rear of the shoe 60 immediately above the heel portion.

The side portions 13 of this supporting and tension member have zigzag bends 15 forming vertically resilient side portions immediately above and controlling the side 65 portions of the bridge member 11 to which their lower angular extremities are connected, and the side portions 13 may also be bent above their said resilient portions to form attaching rings 16 which lie against 70 opposite sides of the shoe 10 and are adapted for the adjustable connection of the opposite ends of an adjusting member preferably in the nature of a strap or similar flexible connection.

This strap or flexible connection 17 is adapted to extend across the front portion of the shoe at or slightly above the instep and serves to hold the arch support in place and also, by adjustable connection of its 80 ends, adjust the supporting tension upon the arch engaging bridge as the user may desire.

It is obvious that the arch support as provided by my invention, formed and shaped 85 as shown and described is capable of ready application with one end of a flexible strap or connection 17 detached by simply shifting the same over the heel portion of a shoe and then tying or otherwise adjustably 90 connecting the free end of the strap to the required or desired tension.

It is also equally obvious that detachment and removal of my improved device may take place with equal readiness and 95 ease and that adjustment of its tension from time to time in use can be easily and quickly accomplished.

It is further obvious that the flexible nature of the tension and supporting member, 100 with its vertically yielding side portions will adapt itself to various sizes and shapes of shoes without trouble and that the invention also readily yields with foot movements and is particularly useful to persons 105 whose work or business requires that they be upon their feet for long periods at a time.

I claim:

1. An outside arch support for shoes including a bridge member arranged to extend 110 transversely beneath the arch of a shoe, a supporting member of inverted U-shape

having vertically resilient side portions attached at their lower ends to the sides of the bridge member and an upper portion arranged to extend rearwardly across the heel 5 of a shoe, and a flexible member adjustably connected at its ends to the sides of said supporting member and adapted to extend across the instep of a shoe.

2. An outside arch support for shoes including a supporting member of inverted U-shape having its sides provided with a plurality of zigzag bends forming flexible sections, a bridge member extending transversely between and connected to the lower 10 ends of said side members, and a flexible retaining member adjustably connected at its ends to the side portions of the supporting member above its resilient bends.

3. An outside arch support for shoes including a supporting member of inverted U-shape having bent portions at its opposite 15 sides forming resilient sections, a trans-

versely disposed bridge member connected at its sides to the lower portions of the sides of said supporting member, said supporting 25 member having its said side portions provided with bends forming attaching rings above its said resilient sections, and a retaining member of flexible nature adjustably connected at its ends to the said attaching 30 rings.

4. An outside arch support including an arch engaging bridge member, a supporting member of inverted U-shape whose side portions have integral spring sections and 35 engage the sides of the bridge member at their lower ends, and an attaching and adjusting member adjustably connected at its ends to the said side portions above their spring sections, as described. 40

In testimony whereof I have affixed my signature.

QUINCY D. SCOTT.
